EMBROIDERED TEXTILE FABRIC

Filed Nov. 16, 1945

ANTON WALTER,
INVENTOR,

BY

Thomas A. Richards

ATTORNEY

UNITED STATES PATENT OFFICE

144,434

DESIGN FOR AN EMBROIDERED TEXTILE FABRIC

Anton Walter, New York, N. Y.

Application November 16, 1945, Serial No. 123,817

Term of patent 3½ years

(Cl. D92—1)

To all whom it may concern:

Be it known that I, Anton Walter, a citizen of the United States of America, residing in New York city, county of New York, and State of New York, have invented a new, original, and ornamental Design for an Embroidered Textile Fabric, of which the following is a specification, reference being had to the accompanying drawing, forming part hereof, wherein the figure is a plan view of an embroidered textile fabric showing my new design.

I claim:

The ornamental design for an embroidered textile fabric, substantially as shown.
